Primary Examiner—Mark A Goodwin*(74) Attorney, Agent, or Firm*—Gardere Wynne Sewell, LLP(57) **CLAIM**

The ornamental design for a commodity caddy, as shown and described.

DESCRIPTION

FIG. 1 is a reduced perspective view of a commodity caddy showing my new design in use condition in an open dumping position;

FIG. 2 is an enlarged front perspective view thereof;

FIG. 3 is a rear perspective view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a reduced perspective view of a commodity caddy showing my new design in use condition and in closed transporting position;

FIG. 9 is an enlarged front perspective view thereof;

FIG. 10 is a rear perspective view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines are for illustrative purposes only and form no part of the claimed design.
